TIE RACK

Le Roy G. Zajicek, Cicero, Ill.

Application July 2, 1954, Serial No. 31,269

Term of patent 7 years

(Cl. D33—8)

Fig. 1

To all whom it may concern:

Be it known that I, Le Roy G. Zajicek, a citizen of the United States, residing at Cicero, in the county of Cook and State of Illinois, have invented a new, original, and ornamental Design for a Tie Rack, of which the following is a specification; reference being had to the accompanying drawing, forming a part hereof.

I claim:

The ornamental design for a tie rack, as shown.
